MOUNTING FOR WHIP ROLLS

Oscar V. Payne, Leicester, Mass., assignor to
Crompton & Knowles Loom Works, Worcester,
Mass., a corporation of Massachusetts

Application June 17, 1939, Serial No. 279,712

15 Claims. (Cl. 139—114)

This invention relates to improvements in the mounting for whip rolls more particularly on wide looms and it is an important object of the invention to provide a mounting for a whip roll which will render it responsive to small variations in warp tension.

In wide looms of the type employed for the weaving of such fabrics as felt it has heretofore been customary to mount the whip roll in stationary bearings and employ a type of let-off which depends in no way for its operation upon movement of the whip roll. Such let-offs have not been entirely satisfactory since the whip roll has not been able to move either forwardly to accommodate temporary high warp tension or rearwardly to absorb any excess warp which may have been released by the let-off. In the let-off shown in my prior Patent No. 2,184,059, issued December 19, 1939 I have shown a let-off which operates satisfactorily to maintain uniform warp tension, and in which the whip roll is movable in response to warp tension demands. As used up to the present time the whip roll has been short enough to be supported at its ends only. In wide looms, however, it is necessary to support the whip roll at one or more points intermediate its ends, and it is an important object of my present invention to provide means by which a long whip roll can be used in connection with a let-off motion of the type shown in the aforesaid patent application.

Looms of the type to which my invention more particularly applies have warp beams of large diameter, and this necessitates the location of the whip roll very close to the beam heads and the yarns of a full beam. As a result of this relation there is very little space between the whip roll and the full beam and I have found it necessary to support the latter for movement on some form of mounting which occupies very little space vertically. To accomplish this result I have used a pair of horizontal links pivoted together, one link being supported by a fixed part of the loom while the other link is connected to the whip roll. The horizontal motion of the whip roll thus provided makes it possible for me to use horizontally swinging levers having force transmitting relation with the whip roll. By using the links to be set forth in detail hereinafter I find that a whip roll thirty feet or more in length can be moved with a very small force.

In order to provide for horizontal motion of the ends of the whip roll I may use the links already described, but in actual practice have found it desirable to employ roller bearings which are held

in a fixed carrier on the loom frame and receive the down pressure of a shoe supporting the whip roll. By this construction the whip roll can be moved back and forth in the loom by the application of very light forces. While I have shown the link suspension of the intermediate parts of the whip roll and the roller bearings for the ends thereof, I do not wish necessarily to be limited to this arrangement and I wish it to be understood that either form of suspension can be used throughout the length of the whip roll.

In order to provide an efficient and cheap form of roller bearing I employ a chain the cross bars of which carry rollers. The links of the chain project above and below the rollers to be in contacting relation with roller engaging flanges, one on the fixed support and the other on the shoe. In this way the side links of the chain are utilized to limit endwise motion of the whip roll, and the fact that the links are pivoted on each other makes it possible for the rollers to adapt themselves to any irregularities which may exist in the engaging surface of the flanges above and below the rollers.

In the preferred form of the invention I use a series of bell crank levers which are operated by a transverse rod connected to the let-off, and these levers act on the whip roll at spaced points during the operation of the loom. In a modified form of my invention I eliminate the levers and connect the transverse rod directly to the rings. This latter construction not only eliminates the levers but also provides an equalizer by which the amount of motion of the links of each pair is the same, thus insuring a parallel back and forth motion of the whip roll.

With these and other objects in view which will appear as the description proceeds, my invention resides in the combination and arrangement of parts hereinafter described and set forth.

In the accompanying drawings wherein two forms of the invention are shown,

tion of the chain and adjacent parts taken on line 7—7, Fig. 5, and

Fig. 8 is a view similar to a portion of Fig. 1 but showing a modification of the invention.

5 The whip roll and mounting therefor to be described has been used in connection with a let-off the general features of which are shown in my prior Patent No. 2,103,821 as modified by the structure shown in my prior Patent No. 2,184,059, issued December 19, 1939, and sufficient description will be given of the let-off to set forth one use for the whip roll and its mounting. I do not wish to be limited in the practice of my invention to the particular let-off with which it is 10 shown herein and it is to be understood that the let-off parts are given merely to illustrate one way in which the movable whip roll can be used to control feeding of the warp threads.

Referring to the drawings, particularly Figs. 20 1, 3 and 4, I have shown a loom frame 10 carrying a rearwardly projecting bracket 11 to receive the gudgeon 12 of a warp beam 13. A large gear 14 moving with the beam meshes with a smaller gear 15 on a fixed stud 16. Fast with the gear 15 is another gear 17 meshing with a pinion 18 on a fixed stud 19. Another gear 20 fast with the pinion 18 meshes with pinion 21 fast on shaft 22 to which is also fixed a star wheel 23. An escapement 24 having upper and lower teeth 25 and 26, respectively, for the star wheel oscillates loosely at 30 with respect to an escapement lever 31. The latter is movable about a fixed axis 32 and has a front arm 33 through which passes loosely the lower end of a rod 34. The latter has a collar 35 secured thereto under arm 33 so that upward motion of rod 34 will rock the shoe 29 away from the arcuate face 28.

335 340 A compression spring 36 surrounds the lower end of rod 34 and presses against the arm 33 by action of a sleeve 37 loose on the rod and held adjustably against the spring by a manually operated nut 38 threaded on the rod 34. The latter is pivoted as at 39 to a pressure lever 40, see Fig. 4, movable vertically about a fixed pin 41. A connector 42 attaches the right end of lever 40 as viewed in Fig. 4 to a weight lever 43 which rocks about a fixed stud 44. The pivotal connection 45 between the connector 42 and the weight lever 43 is located between the stud 44 and the outer or right end of lever 43 as viewed in Figs. 1 and 4 to which is attached an adjustable weight 46. The axis of stud 44 is horizontal so that lever 43 moves in a vertical plane and the upper arm 47 thereof is attached to a connector rod 48 which extends across the loom.

360 The rod is pivotally connected to a plurality of forwardly extending arms 50 of bell crank levers 51 each movable in a horizontal plane about a vertical pin 52 held in a bracket 53 supported by fixed structure. As indicated in Fig. 1 this fixed structure may comprise a plurality of webs 54 which form part of the loom frame as is customary in wide looms. A bracing bar 55 may be secured to the loomsides and extends through and supports the webs 54. Each of the bell crank levers has a laterally extending arm 56 to exert a rearward pressure on the whip roll designated generally at R when the latter is to be moved rearwardly to compensate for warp slackening. When the whip roll is moved forwardly by increasing warp tension the arms 56 are also moved forwardly and rock their levers 51 to move the 70 rod 48 to the left as viewed in Fig. 1, or away

from the let-off mechanism and in a direction to raise the weight.

The matter thus far described may be substantially the same as that shown in my previously mentioned patent and application and operates 5 briefly as follows:

When warp is consumed during normal weaving the whip roll R is moved forwardly from the dotted to the full line positions of the roll R, Fig. 3. During this time the rod 48 moves to the left, see Fig. 1, to rock lever 43 in a direction to lift weight 46. As the weight rises lever 40 is lifted to raise rod 34, thereby lowering shoe 29 for the purpose of releasing the arcuate surface 28. The escapement 24 then oscillates as set forth more 10 fully in my aforesaid patent and application to permit the warp beam 13 to move in a clockwise direction as viewed in Fig. 3 in response to the tension of the warp threads. This slackening of the tension of the warp threads permits a rearward motion of the whip roll R induced by weight 46 acting through rod 48 and the levers 51. The rearward motion of arms 56 is transmitted to the whip roll by means to be described. During descent of the weight lever 43 rod 34 is lowered and a downward force exerted on arm 33 by spring 36 and rocks lever 31 to reestablish engagement between the arcuate surface 28 and the shoe 29. When the pressure of the shoe prevents further rocking of the escapement the warp beam 13 is temporarily locked in fixed angular position.

39 As previously stated, application of a let-off of the type employing a movable whip roll to a wide loom having a large warp beam necessitates provision for mounting the whip roll so that it can move as described even though located very close to the warp beam. I have set forth herein one type of support for the ends of the whip roll and another type of support for the intermediate portions thereof to illustrate two constructions by which the whip roll may be mounted for horizontal motion. Since the supports for each end of the whip roll are substantially the same I will describe but one of them in detail, namely, that 40 located at the let-off end of the loom.

In carrying into effect that part of my invention relating to the end roller bearings I provide a bracket 60 secured to each end of the loom frame. Since the bearings are the same at both 50 ends I will describe but one. A bearing stand 62, bolted to bracket 60, see Figs. 3 and 4, has bolts 63 passing therethrough for holding a horizontal bearing 64 in fixed position. This bearing may be formed as shown in section in Fig. 4 and has 55 an oil chamber 65 in which is located a pair of roller chains 66. These chains may be of the usual type of roller chains and comprise side links 67 and cross bars 68 on which are located rollers 69. The latter are free to turn on the 60 cross bars and rollingly engage a rail 70, one for each chain, set into the horizontal stand 64 and held therein by screw 61. The rails extend back and forth in the loom in the general direction in which the whip roll moves. The ends of 65 the chains are connected together by a rod 71 which moves backwardly and forwardly with the chains between front and back stops 72 and 73, respectively, on bearing 64. By the mechanism just described the chains are limited as to back 70 and forth motion, or motion to the left and right in Fig. 5.

The whip roll has attached to the underside of the end thereof a foot 75 with an arcuate plate 76 fastened to the end of the whip roll by a bolt 75

71. A second rail 78 for each chain is set into the underside of the foot 75 and projects into a chamber 79 formed in the foot. The rails 78 are held to the foot by screws 80 similar to screws 56. There is a rail 78 above each rail 70 and the rollers 69 of the chains are located between the rails so that the weight at the end of the whip roll is transmitted from the foot through the rail 78 to the rollers 69 and from the latter to rail 70.

10 By reason of the construction described in connection with the chains it will be understood that the foot 75 can move forwardly and backwardly or to the right and left, respectively, in Fig. 3, with a minimum of friction because of the 15 action of the rollers 69. It is to be understood that each end of the whip roll is provided with a support similar to that just described in connection with the chains.

For supporting the intermediate parts of the 20 whip roll I employ a different construction such as shown for instance in Figs. 1 and 6. Each support 53 is provided with a pair of vertically spaced ears 85 between which extends a vertical pivot pin 86 passing through the hub 87 of a link 89. The outer end of the link which is remote from the pin 86 is forked as at 90 and has passing therethrough a vertical pin 91 which also passes through the hub 92 of a second link 93. The link 93 has a second hub 94 which is located between the vertically spaced arms 95 and 96, respectively, of a carrier 97 having an arcuate foot 98 secured to the front curved surface of the whip roll as indicated in Fig. 3 at 99. The adjacent parts of the whip roll R therefore are supported from the stand 53 by reason of the 30 links, and vertical pins, and the carrier.

Each carrier 97 is provided with a horizontally adjustable pressure screw 100 which is in contact with the corresponding arm 56. By this 40 connection pressure is transmitted from the rod 48 to the intermediate parts of the whip roll, while the links 89 and 93 support the central portion of the whip roll for horizontal motion in response to the movements either permitted 45 or caused by the levers 51. It will be seen by referring to Fig. 1 that I have indicated two of the link suspensions for the intermediate portions of the whip roll R and that the description given in connection with one of them applies to both, but I wish it to be understood that I may use as many of these suspensions as the 50 width of the loom requires.

In order that the rod 48 may be supported throughout its length I provide intermediate rolls 55 105 carried by a stand 106 secured to an auxiliary frame 107 which may be connected to the cross brace 55 or in any other way secured to a fixed part of the loom frame. The rolls may be concave as suggested in Fig. 2 and are so placed 60 as to prevent sagging of the rod 48.

By referring to Fig. 7 it will be seen that the chain serves to prevent longitudinal or endwise motion of the whip roll. As shown in that figure the chain links 67 project beyond the rollers 69 65 so that they engage the top and bottom rails 78 and 70, respectively. Any tendency of the whip roll to move endwise will cause engagement between the top rail and the links 67 which project below the roll. In this way the chain and its links provide not only a roller bearing but also limit endwise motion of the whip roll. The links 67 further serve the usual purpose of keeping the rollers spaced as shown in Fig. 5.

The foregoing description has related to the 75 preferred form of the invention wherein I use

the bell crank levers 51, but if desired I may omit these levers and provide the modified form set forth in Fig. 8. In that figure the whip roll R is provided with a series of carriers 115 to each of which is pivoted a link 116 as at 117. Each 5 link 116 is pivoted as at 118 to a second link 119 pivoted as at 120 to a fixed part 121 of the loom structure corresponding to the brackets 53. A rod 122 similar to rod 48 is attached to each pair of links 116 and 119 at the pivotal connection 10 118, and rod 122 is extended to have connection with the lever 43 in a manner similar to rod 48.

In this modification the links 116 and 119 together with the parts to which they are connected may be made in a manner similar to that set 15 forth in Fig. 6 for the preferred form of the invention, and it will be understood that the pivots are vertical and of sufficient strength to support the whip roll.

In operation, the whip roll will move back and forth as already described in response to variations in warp tension. Assuming that the whip roll is in the dotted line position shown in Fig. 3, the links 89 and 93 of the preferred form of the invention will be at a relatively large angle to 20 each other, and the shoe 75 at each end of the whip roll will be moved to a rear position. As warp is consumed the whip roll moves forwardly to the full line position of Fig. 3, the links turning with respect to each other around their common pivot 91 and the angle between them being reduced. At the same time the rail 78 rolls forwardly over the tops of the rollers 69 and the latter roll along the bottom rail 70 at a rate substantially one-half that of the advance movement of the whip roll. During this advance of the whip roll the rod 48 is moved to the left as viewed in Fig. 1 to raise the weight 46. When the weight descends as already described the levers 51 will exert their pressure on the whip 30 roll to move the same rearwardly and the links 89 and 93 will spread and the rail 78 will slide rearwardly. The lever arm 56 at each end of the whip roll engages a horn 125 on the adjacent foot 75 which serves the same purpose as 40 the pressure screws 100.

From the foregoing it will be seen that I have provided a mounting for a whip roll so constructed as to permit the roll to be moved by the very slight force. It will also be seen that the mounting of the whip roll includes horizontally moving parts which permit the use of the horizontal levers 51 which can be proportioned to set up a proper relation between the motion of the whip roll and the vertical movement of the weight 50 55 forming part of the let-off. It will also be seen that I have provided a roller bearing of very simple form employing a chain having rollers on its cross bars and wherein the chain links not only space the rollers to insure free rolling 60 thereof but also serve to prevent endwise movement of the whip roll as will be understood from an inspection of Fig. 7. Furthermore, the bar 71 causes the chains to roll together over the rails and cooperates with stops 72 and 73 to limit 65 end motion of the chains and thereby prevent the latter from becoming improperly placed with respect to the rails 70 and 78. In the modified form of the invention the bell crank levers 51 are eliminated and the rod which is connected to 70 the let-off lever 43 is connected directly to the links 116 and 119 for the purpose not only of moving the links positively to create backward and forward movements of the whip roll, but also to insure the same degree of motion on each pair 75

of links so that the whip roll will have a parallel motion throughout its length.

Having thus described my invention it will be seen that changes and modifications may be made therein by those skilled in the art without departing from the spirit and scope of the invention and I do not wish to be limited to the details herein disclosed, but what I claim is:

1. In a loom, a whip roll movable backwardly and forwardly in the loom in response to variations in warp tension, a support fixed to the loom, a foot fixed to the whip roll, and a chain located between the foot and the support and having roller links to engage the support on the foot, the latter rolling on the rollers as the whip roll moves back and forth and the rollers of the chain transmitting the pressure of the whip roll and foot to the support.
2. In a loom, a whip roll movable backwardly and forwardly in the loom in response to variations in warp tension, a support fixed to the loom and having a flange extending in the direction of the back and forth motion of the whip roll, a foot secured to the whip roll and having a second flange parallel to and above the first flange, and a chain having roller links between the flanges, the flange of the foot rolling on the rollers when the whip roll moves backwardly and forwardly and the rollers transmitting the pressure of the whip roll and foot to the first flange on the support.
3. In a loom, a whip roll movable backwardly and forwardly therein in response to variations in warp tension, a stationary rail extending transversely of the whip roll, a chain mounted on said rail and having side links extending below the top of the rail and having also transverse rollers spaced apart from each other by the links, and a second rail fixed with respect to the whip roll and resting on the rollers of the chain and projecting below the tops of the links, the whip roll and rail fixed with respect thereto rolling over the tops of the rollers of the chain and said rollers rolling along the fixed rail when the whip roll moves backwardly and forwardly in the loom, and engagement between the rails and the side links of the chain limiting motion of the whip roll in the direction of the length thereof.
4. In a loom, a whip roll movable backwardly and forwardly in the loom in response to variations in warp tension, a stationary rail below the whip roll extending transversely of the latter, a chain having spaced rollers resting on the rail, a second rail above the first rail and having contact with the tops of the rollers, said second rail rolling on the rollers and the latter rolling on the first rail when the whip roll moves backwardly and forwardly in the loom, and means to limit motion of the chain with respect to the first named rail.
5. In a loom, a fixed support on the loom, a whip roll to be moved horizontally in response to variations in warp tension, a plurality of supporting connections between the fixed support and whip roll, each connection comprising jointed normally oblique members one of which is pivoted to the fixed support and the other of which is pivotally connected to the whip roll, and an equalizer connected to the supporting connections to cause the members of each supporting connection to have the same angular relation as the members of the remaining supporting connections.
6. In a loom, a fixed support on the loom, a whip roll to be moved horizontally in response

to variations in warp tension, a plurality of supporting connections between the fixed support and whip roll, each connection comprising jointed normally oblique members one of which is pivoted to the fixed support and the other of which is pivotally connected to the whip roll, the members of each connection being pivoted together and moving angularly with respect to each other when the whip roll moves toward or from the fixed support, and an equalizer attached to the connections to cause the latter to impart equal movements to the whip roll.

7. In a loom, a fixed support on the loom, a whip roll to be moved horizontally in response to variations in warp tension, a plurality of supporting connections between the fixed support and whip roll, each connection comprising jointed normally oblique members one of which is pivoted to the fixed support and the other of which is pivotally connected to the whip roll, the members of each connection moving angularly with respect to each other when the whip roll moves toward or from the fixed support, and an equalizer extending parallel to the whip roll and attached to the connections to cause the latter to impart equal movements to the whip roll when the equalizer moves in a direction parallel to the whip roll.

8. In a loom, a fixed support on the loom, a whip roll to be moved horizontally in response to variations in the warp tension, a plurality of pairs of supporting links, one link of each pair connected pivotally to the fixed support and the other link of each pair connected pivotally with respect to the whip roll, a pivotal connection between the links of each pair, and an equalizer connected to the pivotal connections between the links to cause the links of the pairs to have the same amount of relative angular motion when the equalizer is moved.

9. In a loom, a fixed support on the loom, a whip roll to be moved horizontally in response to variations in the warp tension, a plurality of pairs of supporting links, one link of each pair connected pivotally to the fixed support and the other link of each pair connected pivotally with respect to the whip roll, a pivotal connection between the links of each pair, and an equalizer comprising a rod parallel to the whip roll and connected to the pivotal connections between the links to cause the links of the pairs to have the same amount of relative angular motion when the equalizer is moved.

10. In a loom, a whip roll movable backwardly and forwardly in the loom in response to variations in warp tension, a pair of parallel spaced fixed rails extending in the direction in which the whip roll moves, a chain including spaced rollers on each rail, a foot on the whip roll, a pair of rails on the foot, one rail over each of the fixed rails, said rails resting on the rollers of the chain, connecting means to cause the chains to move in unison along the fixed rails, and stop means cooperating with said connecting means to limit motion of the chains along the rails.

11. In a loom having a whip roll extending across the loom and over which a sheet of warp extends toward the front of the loom, the loom having a support for each end of the whip roll with respect to which the roll moves horizontally in response to variations in warp tension, that improvement comprising an intermediate support for the whip roll in front of the latter and under the warp sheet and including a pair of

- jointed links one of which is supported for horizontal pivotal motion with respect to the loom and the other link of which is supported for horizontal pivotal motion by the first link, and 5 a supporting pivotal connection between the said other link and an intermediate part of the whip roll, the links moving horizontally with and supporting the intermediate part of the whip roll as the latter moves horizontally.
- 10 12. In a loom having a whip roll extending across the loom and over which a sheet of warp extends toward the front of the loom, the loom having a support for each end of the whip roll with respect to which the roll moves horizontally in response to variations in warp tension, that improvement comprising a horizontal whip roll supporting link supported by and movable pivotally with respect to the loom under the warp sheet and in a horizontal plane, a second whip 15 roll supporting link connected to the whip roll and movable horizontally under the warp sheet, and a vertical pivotal connection between the links by which the first link supports the second link, the links moving horizontally with and supporting the whip roll as the latter moves horizontally. 20
13. In a loom having a whip roll extending across the loom and over which a sheet of warp extends toward the front of the loom, the loom 25 having a support for each end of the whip roll with respect to which the roll moves horizontally in response to variations in warp tension, that improvement comprising a pair of links, a vertical pivotal connection between the links by 30 which one link supports the other link, one end of said one link supported by and pivotally mounted for horizontal swinging relatively to the loom, and a vertical pivotal connection between the other link and an intermediate part of the whip 35 roll between the ends thereof, said links located under the warp sheet and in front of the whip roll and said links moving horizontally with and supporting the intermediate part of the whip roll as the latter moves horizontally. 40
14. In a loom having a warp beam and a whip roll extending across the loom and over which a sheet of warp from the beam extends toward the front of the loom, the loom having a support for each end of the whip roll with respect to which the roll moves horizontally in response to variations in warp tension, that improvement comprising an intermediate support for the whip roll in front of the latter and between the warp sheet and the beam, said support including a pair of jointed links one of which is supported for horizontal pivotal motion with respect to the loom and the other link of which is supported for horizontal pivotal motion on and with respect to the first link, and a supporting pivotal connection between the said other link and an intermediate part of the whip roll, the links moving in the space under the warp sheet horizontally with and supporting the intermediate part of the whip roll as the latter moves horizontally. 5
- 10 15. In a loom having a whip roll movable horizontally in response to variations in the tension of a sheet of warp extending over the whip roll and forwardly therefrom, a stationary support forming part of the loom structure, a horizontal 15 link, a pivotal connection between one end of the link and the support to hold the link against downward displacement and around which the link moves pivotally, a second link, a pivotal connection between the other end of the first named 20 link and one end of the second link to prevent downward displacement of the second link relatively to the first link and around which the second link turns with respect to the first link, and a supporting connection between the other 25 end of the second link and the whip roll, said links normally being angularly disposed with respect to each other and movable horizontally with respect to each other and the support during horizontal motion of the whip roll to support 30 the latter against downward displacement. 35

OSCAR V. PAYNE.
